PORTABLE HOIST

Paul A. Ketchpel, West Englewood, N. J., assignor
to Ketchpel Engineering Company, West Engle-
wood, N. J., a corporation

Application January 27, 1949, Serial No. 73,103

7 Claims. (Cl. 214—95)

1

This invention relates to hoists and more specifically to one suitable for lifting beer barrels from ground to truck level where no loading platform exists.

It is an object of this invention to provide a hoist that is portable, light weight in construction and easily moved throughout different areas of the plant, such as in a yard or in a cooling room or other parts of a plant.

Another object of this invention is to provide a hoist which is versatile and rapid in operation and which may be moved close up against the rear end of a truck body.

Another object of the invention is to provide a hoist which is provided with a loading platform which receives its load from one side and automatically discharges it at the other side.

It is another object of the invention to provide a hoist having means suitable for mounting any one of a number of standard electric hoist motors for use as its prime mover.

It is a further object of the invention to provide a combination of electrical controls and adjustable mechanical controls for automatically stopping the upward or downward movement of the platform.

It is another object of the invention to provide mechanism for automatically tilting the platform of a hoist to discharge barrels therefrom so that they will roll to the front end of a truck for being stacked manually.

It is a further object of the invention to provide a frame work for a hoist which will be economical in its consumption of metal and economical to fabricate and so proportioned in its design that it is capable of supporting elevated loads without danger of tipping.

It is also an object of the invention to provide a high load capacity weldment for the frame of a hoist which comprises of a horizontal U section and an inverted vertical U section, all of which can be fabricated of common metal shapes.

I attain these objects by mechanism illustrated in the accompanying drawings in which:

Figure 1 is a front elevation of the machine.

Figure 2 is a plan view of the machine as it appears in Figure 1 with the electric extension cord and rack removed.

Figure 3 is an end elevation view of the machine shown in Figure 1 with the electric extension cord and rack removed.

Figure 4 is a vertical section of the machine taken along the line 4—4 on Figure 1.

Figure 5 is an isometric view of the frame weldment.

2

Similar numerals refer to similar parts throughout the several views.

The mechanism herein disclosed provides a light weight portable electric hoist which may be used in yards where the terrain is rough and uneven and may be easily moved to all other parts of a plant where electric outlets exist for plugging in its extension cord to provide its electric current to raise its platform.

10 Loaded beer barrels weigh about 260 lbs. each and are frequently loaded on and off of trucks by beverage distributors who do not have loading platforms. Thus it is a slow and laborious job to raise these barrels from ground to truck body level requiring a two man team. With my invention after the barrels are rolled on to the platform an electric motor is used to raise the beer barrels and cause them to roll off the platform at the top of its stroke.

15 Referring now to the drawings the machine 10 has a frame 11, comprising a U-shaped horizontal base member 12 including the two side legs 13 and the rear cross piece 14; an inverted U-shaped upright truss member 15 including vertical columns 16 and an overhead beam 17; and brace members 18 extending down from the upper portion of said truss members 15 at each side and connecting with the U-shaped horizontal base section 12 of said frame 11. The machine 20 may be further strengthened with shelf supports 19 welded in between the braces 18 and the columns 16.

25 Caster plates 20 are welded to the far corner of the U-shaped horizontal base 12 to which the large wheeled ball bearing swivel casters 21 are bolted.

30 The overhead beam 12 may be constructed of two channels 22 spaced apart, spanning between and welded on to the upper ends of the vertical columns 16. A double sheave wheel 23 is supported on pins 24 mounted in holes 25 in said channels 22 at the right side thereof and a single sheave wheel 26 is mounted likewise at the other end of the overhead beam 17.

35 A universal motor mounting 28 is provided to accommodate one of a choice of many standard type electric hoist motors for furnishing the power for hoisting loads with this invention. As shown a channel shaped bracket 29 is welded to one of the vertical columns 16 and a well known electric motor 30 is suspended thereto by the bolt 31.

40 The lift chain 32 of this standard electric prime mover is shortened, then assembled around a 50 sprocket 33 mounted for rotation on a pin 34

supported in bearings 35 welded to one of the vertical columns 16. The remote end 36 of the chain 32 extends up to the top of the column 16, where it is attached by a clamp 37 to the loop 38 formed at the motor end of the long cable 40 and short cable 39 which run over the double sheave wheel 23. The other end of the short cable 39 extends down the inner side of the vertical column 16 on the right side of the machine and is pivotally connected by a pin 43 mounted in the right end wall 44 of the platform 45. The long cable 40 extends across to the left side of the machine where it runs on the single sheave wheel 26 and then extends down and is attached to the left end wall 46 of the platform 45 in the same manner as described before.

As best shown in Figures 1 and 4 the platform 45 is of novel construction and comprises left and right end walls 44 and 46 welded on to a tray 47 extending across from one side of the machine to the other and preferably being wide enough to accommodate two beer barrels laid endwise as shown in dot and dash lines at 48. The tray is provided with a ramp 49 at the front side of the machine to facilitate rolling the barrels on to the tray. A trough-like depression 50 is formed in the tray 47 and provides means for holding the barrels on the platform 45 when it rises.

It should be noted that the edges of the end walls 44 and 46 and the flange 51 formed on the tray member 47 of the platform 45 rests on the floor when in its lower most position. This flange 51 and the sloping wall 52 stiffen the tray and permit the use of light weight metal.

Trunnion 55 extending outwardly from the end walls 44 and 46 and engage the vertical columns 16 for guiding the platform 45 as it moves up and down. The columns 16 are shown constructed of I-beams which provide suitable tracks 56 in which wheels 57 mounted on the trunnions 55 may engage.

The electric motor 30 is set in motion by raising the manual switch lever 60 which is pivoted to the bracket 29. The manual switch lever 60 is connected by a link 61 to a fulcrum lever 62 pivoted on a shaft 63 which is in turn connected by a link 64 to the automatic switch lever 65 mounted on the pivot pin 58. Raising the manual switch lever 60 or lowering the automatic switch lever 64 will cause the motor sprocket 66 to rotate and pull in its chain 32. A receptacle 59 is provided to hold the pulled in chain.

The automatic switch lever 65 has a forked end 67 which straddles a rod 68 which is mounted in bearings 69 welded to the vertical column 16. A stop collar 70 is mounted at the top of rod 68 to prevent it from falling through the bearings 69.

As the tray 47 rises, the lug 71 welded on the tray 47 engages a projecting lug 73, a part of a collar 72 mounted on the rod 68, and raises the rod 68 and causes the collar 74 to raise the automatic switch lever 65, shut off the motor 30 and apply the brake 27 which is standard equipment on the prime mover.

As the tray 47 rises, tilting bosses 75 welded on each end wall 44 and 46, engage stop blocks 76 causing the tray 47 to pivot about trunnions 55 in track 56 and tilt the tray 47 to discharge barrels 48 on to the flange of a truck.

The stop blocks 76 are adjustably mounted on braces 18, and by loosening screw 77 with handle 78 the tilting blocks 76 may be raised or lowered to cause the tray 47 to discharge its load at the desired height.

Lowering manual switch lever 60 will cause

motor sprocket 66 to rotate and pay out chain 32 until the loop 79 of the chain 32 pulls up on the short end 93 of the automatic switch lever 65 shuts off motor 30 and applies brake 27 as the platform 45 reaches its lowest position. A spring 86 is fastened between the end of chain 32 and bolt 87 on motor 30 to take strain on chain 32 if the motor 30 overtravels.

In operation for loading trucks, the hoist is pushed up against the tail gate of the truck until the braces 18 rest against the edge of the tail gate. Barrels roll from the tray on to the floor of the truck. However, when raising barrels to stack them in a cooling room it is not possible to move the platform very close to the last barrel in the stack. Therefore, a transfer shelf 80 is provided for spanning the gap between the platform and the barrel on which the next barrel is to be placed.

The transfer shelf 80 is constructed with side plates 81 having hooks 82 at their upper end and support legs 83 bent at their lower ends to rest against the braces 18. The floor 84 of transfer shelf 80 has flanges 85 bent at both edges to strengthen same and permit use of light weight metal. The transfer shelf 80 may be attached to braces 18 by canting transfer shelf 80 between braces 18 and engaging the hooks 82 behind the braces 18. The shelf 80 is then lowered until the hooks 82 rest on shelf supports 19 and the lower supporting legs 83 rest against the braces 18. In using the transfer shelf 80 the tilting tray blocks 76 are raised first and adjusted so that platform 45 will be level with the transfer shelf 80 and the motor stop collar 72 is adjusted so motor 30 is shut off before the load is discharged onto platform 84.

An electric extension cord 94 of 50 to 75 feet in length is connected to the motor 30 for plugging into outlets at various parts of a plant. When the cord 94 is not in use it may be conveniently stored on a bracket 95 extending out from the upper end of the right vertical column 16.

It should now be apparent that the above discloses the construction for a machine which may be used to hoist barrels, bags or cases from the ground or floor level to truck bodies, platforms or for stacking such objects in storage areas. Other uses will suggest themselves for this machine which will be covered by the following claims.

The construction disclosed and described represents the preferred and commercial form of the invention but various changes of detail may be made without departing from the scope of the invention.

I claim:

1. In a portable hoist, the combination of a frame comprising a U-shaped horizontal base comprising open horizontal legs and a rear member connecting both of said legs, an inverted U-shaped upright truss comprising vertical open columns and a top horizontal beam member, the lower ends of said vertical columns being mounted on the U-shaped horizontal base approximately midway along the horizontal legs, a platform centrally cradled in said U-shaped base and centrally mounted within the confines of said inverted U-shaped upright truss and suspended by cables supported on pulleys mounted on the horizontal beam members of said inverted U-shaped upright truss, said horizontal and vertical U-shaped frame members being free of crossbraces to provide unobstructed loading and movement of

the platform in said frame, an electric prime mover mounted on said frame for moving said cables, switch mechanism for manually starting the movement of said platform and mechanical means comprising a lug on the platform, a projecting lug on a stop rod mounted on an upright column of the frame, in the path of the first named lug for automatically actuating said switch mechanism for stopping movement of said platform at the end of its upward or downward stroke, and means resiliently resisting overtravel of said prime mover.

2. In a portable hoist, the combination of a frame comprising a horizontal base having horizontal leg members open for unobstructed loading, an upright truss including columns and an overhead beam member, said columns being mounted on the horizontal legs of said member, a platform mounted for up and down movement between said upright columns and suspended by cables which are supported by said overhead beam members, an electric hoist for moving said cables, means for supporting said hoist motor on said frame, trunnions located centrally at the ends of said platform having engagement with the upright columns for vertically guiding said platform, brace members extending down from the upper portion of said truss member at each side and connecting with the rear corners of the horizontal base section, and a transfer shelf mounted between said braces and supported thereby, said horizontal base being U-shape and arranged to permit the platform to be lowered to the floor and cradled in the confines of said U-shape base where the platform may be loaded directly from the floor through the opening at the front side of said frame, and said transfer shelf being located on the rear of said frame for receiving the load discharged from said platform.

3. In a portable hoist, the combination of a frame comprising a U-shape horizontal base having open horizontal legs and a rear member connecting both of said legs, an inverted U-shape upright truss comprising vertical columns open therebetween and connected by an overhead horizontal beam member, all of said frame members arranged to permit loading at the floor level on the front side and discharging on the rear side thereof, a platform mounted centrally between said upright columns, said platform provided with trunnions located centrally at the ends of said platform and providing a pivot for same and having engagement with the upright columns for guiding said platform, cables pivotally attached to said platform for up and down movement thereto, sheave wheels provided on the overhead beam member for supporting said cables, an electric motor mounted on said truss out of the path of said platform, switch mechanism for manually starting the movement of said platform, mechanical means for automatically stopping movement of said platform at the end of its upward or downward stroke, said mechanical means comprising a lug on the end of the platform and a stop rod slideably mounted on the vertical column and extended down to the motor which automatically shuts off the current at the end of the upward or downward stroke of the platform.

4. In a portable hoist, the combination of a frame comprising a U-shape horizontal base having open horizontal legs and a rear member connecting both of said legs, an inverted U-shape upright truss comprising vertical columns open therebetween and connected by an overhead

horizontal beam member, all of said frame members arranged to permit loading at the floor level on the front side and discharging on the rear side thereof, a platform mounted centrally between said upright columns, said platform provided with trunnions located centrally at the ends of said platform and providing a pivot for same and having engagement with the upright columns for guiding said platform, cables pivotally attached to said platform for imparting up and down movement thereto, sheave wheels provided on the overhead beam member for supporting said cables, an electric motor mounted on said truss out of the path of said platform, brace members extending rearwardly down from the upper portion of said columns at each side and connected with the rear corners of the horizontal base section, a transfer shelf mounted between said braces and supported thereby, adjustable stops on said frame, and means on said platform for contacting said stops for tilting said platform when moved thereagainst by said cables, switch mechanism for manually starting the movement of said platform, mechanical means for automatically stopping movement of said platform at the end of its upward or downward stroke, said mechanical means comprising a lug on the end of the platform and a stop rod slideably mounted on the vertical column and extended down to the motor which automatically shuts off the current at the end of the upward or downward stroke of the platform.

5. In a portable hoist, the combination of a frame comprising a U-shape horizontal base having open horizontal legs and a rear member connecting both of said legs, an inverted U-shape upright truss comprising vertical columns open therebetween and connected by an overhead horizontal beam member, all of said frame members arranged to permit loading at the floor level on the front side and discharging on the rear side thereof, a platform mounted centrally between said upright columns, said platform provided with trunnions located centrally at the ends of said platform and providing a pivot for same and having engagement with the upright columns for guiding said platform, cables pivotally attached to said platform for imparting up and down movement thereto, sheave wheels provided on the overhead beam member for supporting said cables, an electric motor mounted on said truss out of the path of said platform, switch mechanism for manually controlling the movement of said motor, said platform being wider than it is deep and having a floor plate formed to provide a loading ramp at the front side thereof, a depression at its central portion into which barrels may be lodged while being hoisted, a floor portion of its rear side sloping downward towards the center when said platform is normally suspended by said cables, said platform having upstanding end walls provided with trunnions extending outwardly to engage the columns of said inverted upright truss, said end walls being provided with pins for attaching the cables to the platform, said end walls provided with projecting lugs, tilting bosses provided on said frame at the desired discharge level in the path of said projecting lugs, said motor and cables being arranged to tilt said platform until its rear floor portion slopes to the rear of the hoist and discharges the barrels from said depression.

6. In an article of manufacture for the purpose described, an integral frame weldment for a portable hoist comprising a U-shape horizontal base having two tubular side legs and a rear

tubular member connecting both side legs, an inverted U-shape upright truss comprising vertical double channel-like columns connected by a beam comprising spaced channels at their upper end, said columns of said inverted U-shape truss members being formed to said tubular legs midway between their ends, tubular-like brace members formed with the upper end of said vertical columns and extending down to said horizontal frame portion and formed with the frame at the rear corners, one of said vertical columns having a motor support formed thereon, said U-shape tubular base portion having caster mounting plates formed on the underside of all four corners.

7. In an article of manufacture for the purposes described a weldment comprising of a horizontal U-shaped base member, an inverted U-shaped upright truss member having the lower ends connected to the side legs of said base member, brace members extending down from the upper portion of said truss at each side and connecting with the rear corners of said U-shaped horizontal base member, said members all welded together to form one integral product.
